EXTENSIBLE TABLE

John H. Yoder, Goshen, Ind., assignor to Barler Metal Products, Inc., a corporation of Indiana

Filed June 12, 1958, Ser. No. 741,569

5 Claims. (Cl. 312—317)

This invention relates to an extensible table and more particularly to a combination cabinet and storable extensible table.

An object of this invention is to provide a new and improved extensible table.

Another object of this invention is to provide a combination cabinet and extensible table having a plurality of table leaves which may be stored within a cabinet frame in nested position and which may be moved to extended positions away from the cabinet to form a flush table top and wherein each leaf top is spaced from the adjacent leaf during retracting and extending movements to avoid marring the table tops, and in which one leaf may be individually extended for its entire width or a portion thereof to form a sturdy table top.

Another object of the invention is to provide a table structure as defined in the preceding paragraph wherein each of the table leaves is mounted for movement in a path toward and away from the cabinet for extending and retracting the table leaves and each of the leaves are mounted for movement in a path transverse to the retracting and extending path to place the leaves in spaced apart vertical relation during the extending and retracting movement and to move the leaves into positions with their tops flush when the leaves are extended to form a smooth table top.

Further objects and advantages will become apparent from the following detailed description taken in connection with the accompanying drawings in which:

Fig. 1 is a perspective elevational view of the combination cabinet and table looking toward the front thereof with the table leaves stored;

Fig. 2 is a plan section of the combination cabinet and table with the table leaves in extended position and taken generally along the line 2—2 in Fig. 3;

Fig. 3 is a vertical section taken generally along the line 3—3 in Fig. 2;

Fig. 4 is a fragmentary side elevational view of the combination cabinet and table similar to Fig. 3 with the table leaves shown in nested retracted positions;

Fig. 5 is a side elevational view on an enlarged scale of the connections between adjacent table leaves and taken generally in the direction of line 5—5 in Fig. 2;

Fig. 6 is a vertical enlarged section taken generally along the line 6—6 in Fig. 2; and

Fig. 7 is a detailed section taken generally along the line 7—7 in Fig. 5.

While this invention is susceptible of embodiments in many different forms, there is shown in the drawings and will herein be described in detail an embodiment of the invention with the understanding that the present disclosure is to be considered as an exemplification of the principles of the invention and is not intended to limit the invention to the embodiment illustrated. The scope of the invention will be pointed out in the appended claims.

As shown in the drawings, a base cabinet indicated generally at 10 houses a plurality of table leaves 11, 12

2

and 13 in telescoped nesting relation when in a retracted condition, as shown in Fig. 4. The table leaves 11, 12, and 13 may be fully extended as shown in Figs. 2 and 3 or a top of a lesser length may be formed by extending less than all the leaves from within the cabinet 10. The end leaf 13 has a pair of legs 14 and 15 supporting the leaf relative to a supporting surface and also has a front panel 16 formed with pulls 17 to enable pulling the table out from the cabinet 10. The cabinet 10 in addition to storing the table leaves has slideable drawers 18 and 19 and a storage area closed by doors 20. The table is shown having three leaves although additional leaves similar to leaf 12 may be used when a longer table is desired.

The cabinet 10 includes a frame having a front opening 25 through which the table leaves 11, 12 and 13 pass in moving into and out of the cabinet.

The table leaves 11, 12 and 13 are formed of relatively thin material such as sheet steel and each may have its top covered with a sheet of plastic material or a coating such as plastic material or enamel, or the like. In order to properly illustrate the table construction, the leaves 11, 12 and 13 have been shown as formed of a material with a thickness greater than is actually used, except in Figs. 5 and 6. This has resulted in an apparent stepped relation at the ends of the leaves as shown in Fig. 2; however, the actual use of proportionately thinner material for the leaves would reduce the offset in the table leaves and provide a table top which when extended would have a substantially uniform width.

The cabinet 10 includes braces 25a which mount guide means in the form of elongated guide tracks 26 and 27 shaped as upstanding channels with the channels outwardly facing and extending to the opening 25 in the cabinet. The guide tracks 26 and 27 rollably mount a carriage having a pair of runners with the runner 28 disposed within the guide track 26, as shown in Fig. 6, and a runner 29 disposed within the guide track 27 (Fig. 2). The runners 28 and 29 are connected by a rear transverse cross brace 30 and a forward transverse cross brace 31.

Each of the carriage runners 28 and 29 rotatably mounts five rollers 32, 33, 34, 35, and 36. The rollers 32 and 34 are mounted to have their periphery extend beneath the runner to engage a bottom flange 37 of the guide track, as shown in Fig. 6. The rollers 32 and 34 rollingly support the runners in their respective guide tracks 26 and 27 for movement between a position within the cabinet, as shown in Fig. 4, and an extended position, as shown in Fig. 3. In order to prevent tipping of the runners when extended the rollers 36 are mounted to extend above the upper sides of the runners and to engage an upper flange 38 of the guide tracks 26 and 27.

As shown in Fig. 3, the rollers 34 and 35 extend beyond the guide tracks 26 and 27 when the carriage is extended from the cabinet and a button 40 of a relatively frictionless material, such as nylon, is mounted on the bottom flanges 37 of the guide tracks outwardly of the path of travel of the rollers 32 and 34. The runners slide on the buttons during part of their movement outwardly of the cabinet 10.

The first table leaf 11 has a top 41 and downturned end walls 42 and 42a and is mounted for movement with the carriage runners 28 and 29 and for movement relative thereto for extension and retraction by means of cam plates 43 and 44 mounted on the inside of the end walls 42 and 42a and which are elongated in the direction of extending and retracting movement of the table leaf. The cam plate 43 coacts with the pair of carriage rollers 34 and 35 while the cam plate 44 coacts with the pair of carriage rollers 32 and 33. The cam plate 43 has a lower step 43a and an upper step 43b. The cam plate 44 has

a lower step 44a and an upper step 44b. The cam plate structure is the same for both end walls 42 and 42a of the table leaf 11. A pair of abutments 45 and 46 are carried on the underside of the table leaf 11. These abutments coact with the cross brace 31 connecting the carriage runners 28 and 29 whereby as the table leaf is extended outwardly from the cabinet the carriage is caused to move with the table leaf for a part of leaf movement and the carriage continues to move until the rear cross brace 30 engages a pair of stops 47, mounted on the inner walls of the guide tracks 26 and 27.

With the first table leaf 11 in extended position the leaf is supported by engagement of the cam guide steps 43a and 44a with the rollers 34 and 32, respectively. As the table leaf 11 is moved into the cabinet the cam plates 43 and 44 move toward the left, as viewed in Fig. 3, relative to the pairs of carriage rollers 34, 35; 32, 33 so as to have the rollers move onto the upper steps 43b and 44b. This will lower the table leaf 11 and during the final inward movement of the leaf the downturned edge wall 50 will engage the carriage brace 31 and move the carriage into the cabinet. As the table leaf 11 is withdrawn from the cabinet the carriage rollers will move onto the lower steps 43a and 44a to raise the leaf and during the final movement of the leaf the carriage will be moved outwardly of the cabinet until the movement is limited by the stops 47 and 48.

The intermediate leaf 12 is mounted on the first leaf 11 for movement therewith and relative thereto during movement between extended and retracted positions and for vertical movement in a direction transverse to the path of extending and retracting movement to move the leaf 12 between a position with its top flush with that of leaf 11 and a position in vertically spaced relation thereto. This movement is accomplished by having the table leaf 12 formed with end walls 55 and 56 each of which are formed with an elongated slot 57 which coacts with a grooved roller 58 mounted one on each of the end walls 42 and 42a of the leaf 11. The end walls 55 and 56 of the leaf 12 each carry a grooved roller 59 which coacts with a slot 60 formed in each of the end walls 42 and 42a of the leaf 11. The slots 57 have their rear ends 57a, nearest the cabinet when the leaf 12 is in extended position, upturned to form a cam while the slots 60 have their front ends 60a, farthest from the cabinet when leaf 11 is extended, downturned to form a cam. Thus during the final extending movement of leaf 12 relative to leaf 11 the leaf 12 will move downwardly because of the cam action of the slots and rollers to place its top in flush relation with the top of leaf 11. Conversely, when leaf 12 is retracted relative to leaf 11 the rollers 58 and 59 travelling in the cam slot ends 57a and 60a, respectively, raise the leaf 12 to a position above the top of leaf 11 so the leaves may move relative to each other without marring the top of leaf 11.

The outer leaf 13 is mounted relative to leaf 12 for movement in the same manner as leaf 12 moves relative to leaf 11 and for this purpose the leaf 13 has end walls 65 and 66 each of which has an elongated slot 67 in each of which is positioned a grooved roller 68 carried on the end walls 55 and 56 of the leaf 12. The end walls 55 and 56 of leaf 12 each has a slot 69 which receives a grooved roller 70 carried on the end walls 65 and 66 of leaf 13. The adjacent ends of these slots are shaped to have the rear ends 67a of slots 67 upturned and the front ends 69a of slots 69 downturned to obtain the movement of leaf 13 between a position with its top flush to the top of leaf 12 and a position vertically spaced therefrom.

The particular form of grooved pulley coacting with an end wall slot is shown in Fig. 7 and in order to associate the grooved roller with the slot each slot has an enlarged opening at an end, as indicated at 75 relative to slot 67, whereby the roller may be moved into operative relation with the slot in initial assembly of the table

leaves. The roller is mounted to the associated end wall by a pin 80 passing through the roller.

It will be seen from the foregoing description that an extensible table is provided in which the table leaves may be stored within a cabinet when not in use and in which a variable length table may be provided by extending a single leaf, a plurality of leaves or all the leaves. When the leaves are in nested relation within the cabinet and during their extending and retracting movements they are in vertically spaced relation so as not to result in engaging and marring the top of any leaf. As the leaves move into fully extended position by a pull on pulls 17 they are vertically shifted relative to each other to result in having their tops flush and immediately upon starting to retract from extended position they are caused to move back into their vertically spaced relation.

As shown in the drawings, each of the table leaves has an exposed top when in extended position and an offset top part at a lower level so as to underlie the top section of the adjacent leaf. It is believed obvious that the leaf flange 50 of each leaf could extend downwardly from the exposed top section and the offset part be omitted.

I claim:

1. A combination cabinet and storable extensible table comprising, a cabinet frame having a front opening, a plurality of table leaves telescopically associated to be nested in spaced relation one above the other within the cabinet frame when in retracted position and disposable in extended position with the leaf tops flush to form a smooth table top extending outwardly from the cabinet frame, means mounting a first of said leaves for movement in a path to extend said first leaf beyond the cabinet frame, a second of said leaves disposed above the first leaf when nested, means mounting the second leaf on said first leaf for movement therewith and relative thereto in a path to extend the second leaf beyond the first leaf and for movement transverse to said path of extending movement to move the second leaf top into and out of flush relation with the first leaf top when extended and before being retracted, respectively, a third of said leaves disposed above the second leaf when nested, means mounting the third leaf on said second leaf for movement therewith and relative thereto in a path to extend the third leaf beyond the second leaf and for movement transverse to said path of extending movement to lower the third leaf and place its top flush with the second leaf top at the end of extending movement and raise the third leaf at the beginning of retracting movement, and legs extending from the third leaf engageable with a supporting surface.

2. A combination cabinet and storable extensible table comprising, a cabinet frame having a front opening and internal guide means at opposite sides extending to said opening, a carriage slidable on said guide means between a first position wholly contained within the cabinet frame and a position partially extending outside the cabinet and beyond the guide means, a plurality of table leaves telescopically associated to be nested in spaced relation one above the other within the cabinet frame when in retracted position and disposable in extended position with the leaf tops flush to form a smooth table top extending outwardly from the cabinet frame, means mounting a first leaf of said leaves on said carriage for movement therewith and relative thereto in a path to extend said first leaf beyond the frame and for movement of said first leaf transversely of said path away from the carriage at the end of said extending movement to raise the leaf top, a second leaf of said leaves disposed above the first leaf when nested, means mounting the second leaf on said first leaf for movement therewith and relative thereto in a path to extend the second leaf beyond the first leaf and for movement transverse to said path of movement and toward the first leaf at the end of the extending movement to lower the second leaf and place its top flush with the first leaf top, a third leaf of said

leaves disposed above the second leaf when nested, and means mounting the third leaf on said second leaf for movement therewith and relative thereto in a path to extend the third leaf beyond the second leaf and for movement transverse to said path of movement to lower the third leaf at the end of the extending movement and place its top flush with the second leaf top.

3. A combination cabinet and storable extensible table comprising, a cabinet frame with a front opening and having internal guide means at opposite sides extending to said opening, a carriage slideable on said guide means between a first position wholly contained within the cabinet frame and a position partially extending outside the cabinet and beyond the guide means, a plurality of table leaves each of a size to fit within the cabinet frame and nested one above another when retracted within the cabinet frame and disposable in extended position with the leaf tops flush to form a smooth table surface, means mounting a first of said leaves on the carriage for movement therewith and relative thereto to an extended position outside the cabinet frame opening, a second of said leaves having supporting legs movable to an extended position farthest from the frame, and means including at least a third one of said leaves connected between said first and second leaves for movement relative thereto and therewith in extending and retracting movements relative to the cabinet and for movement transverse to said last mentioned movement to move the leaf tops into and out of flush relation.

4. A combination cabinet and storable extensible table comprising, a cabinet frame having a front opening and internal guide tracks at opposite sides extending to said opening, a carriage slideable on said guide tracks between a first position wholly contained within the cabinet frame and a position partially extending outside the cabinet and beyond the guide tracks, a plurality of table leaves with downturned end walls telescopically associated to be nested in spaced relation one above the other within the cabinet frame when in retracted position and disposable in extended position with the leaf tops flush to form a smooth table top extending outwardly from the cabinet frame, means mounting a first of said leaves on said carriage for movement therewith and relative thereto in a direction to extend said first leaf beyond the frame, a second of said leaves disposed above the first leaf when nested, means mounting the second leaf on said first leaf for movement therewith and relative thereto in a direction to extend the second leaf beyond the first leaf and for movement transverse to said extending movement and toward the first leaf at the end of the extending movement to lower the second leaf and place its top flush with the first leaf top including, an elongated slot extending along each of the first and second leaf end walls, a guide member in each of said end wall slots and mounted on the adjacent end wall, the slots in the first leaf end walls having their ends farthest from the frame when the leaf is extended downturned and the slots in the second leaf end wall having their ends nearest the frame when the second leaf is extended upturned, a

third of said leaves disposed above the second leaf when nested, and means mounting the third leaf on said second leaf for movement therewith and relative thereto in a direction to extend the third leaf beyond the second leaf and for movement transverse to said extending movement to lower the third leaf and place its top flush with the second leaf top including, an elongated slot in each of said third leaf end walls having upturned ends nearest the frame when the leaf is extended and guide members in said slots mounted on the second leaf end walls.

5. A combination cabinet and storable extensible table comprising, a cabinet frame having a front opening and internal guide tracks at opposite sides extending to said opening, a carriage slideable on said guide tracks between a first position wholly contained within the cabinet frame and a position partially extending outside the cabinet and beyond the guide tracks, a plurality of table leaves with downturned end walls telescopically associated to be nested in spaced relation one above the other within the cabinet frame when in retracted position and disposable in extended position with the leaf tops flush to form a smooth table top extending outwardly from the cabinet frame, means mounting a first of said leaves on said carriage for movement therewith and relative thereto in a direction to extend said first leaf beyond the frame and for transverse movement of said first leaf away from the carriage at the end of said extending movement to raise the leaf top and toward the carriage at the beginning of the retracting movement to lower the leaf top including, elongated guide plates on the inner side of said first leaf end walls having a first step and a second step at different distances from the leaf top, and rollers on said carriage rollingly confining said guide plates for relative movement along the length of the guide plates, a second of said leaves disposed above the first leaf when nested, means mounting the second leaf on said first leaf for movement therewith and relative thereto in a direction to extend the second leaf beyond the first leaf and for movement transverse to said extending movement and toward the first leaf at the end of the extending movement to lower the second leaf and place its top flush with the first leaf top, a third of said leaves disposed above the second leaf when nested, and means mounting the third leaf on said second leaf for movement therewith and relative thereto in a direction to extend the third leaf beyond the second leaf and for movement transverse to said extending movement to lower the third leaf and place its top flush with the second leaf top.
